(57) **CLAIM**

The ornamental design for a pocket watch stand, as shown and described.

DESCRIPTION

FIG. 1 is a front view of a pocket watch stand of the present design;

FIG. 2 is a rear view thereof;

FIG. 3 is a left side view thereof;

FIG. 4 is a right side view thereof;

FIG. 5 is a top view thereof;

FIG. 6 is a bottom view thereof; and

FIG. 7 is a front bottom right perspective view thereof; and,

FIG. 8 is a rear bottom left perspective view thereof.

Portions of the pocket watch stand shown in broken lines form no part of the claimed design.
